Attest

JAMES LICK, OF SAN FRANCISCO, CALIFORNIA.

Letters Patent No. 88,646, dated April 6, 1869.

MACHINE FOR GILDING.

The Schedule referred to in these Letters Patent and making part of the same.

To all whom it may concern:

Be it known that I, JAMES LICK, of San Francisco, in the county of San Francisco, in the State of California, have invented a new and useful Machine for Gilding; and I do hereby declare that the following is a full, clear, and exact description thereof, which will enable others skilled in the art to make and use the same, reference being had to the accompanying drawings, forming part of this specification, in which—

Figure 1 is a plan or top view of my improved machine.

Figure 2 is an end view of the same.

Figure 3 is a vertical cross-section of the same, taken through the line $x\alpha$, fig. 1.

Figure 4 is a detail under side view of a part of the same.

Figure 5 are detail views of the sliding book-block.

Figure 6 is a detail view, illustrating the book-block catches.

Figure 7 is a detail sectional view, taken through the line yy , fig. 1.

Figure 8 is a detail sectional view, taken through the line zz , fig. 7.

Similar letters of reference indicate like parts.

My invention has for its object to furnish a simple and convenient machine for gilding, by means of which the surface to be gilded may be applied to the gold-leaf while in the book, thus rendering the ordinary cutting and handling of the gold-leaf wholly unnecessary; and

It consists in the construction and combination of the different parts of the machine, as hereinafter more fully described.

A is the table, to which the other, or operating parts of the machine are attached.

B are arms, by which the surface to be gilded is held, and which are pivoted at their rear ends, by the rod C, to the supports, or bearings D, attached to the table A.

The arms B are connected to each other by the rod E, so that they may all move together.

The middle arm B is adjustable, and may be slid back and forth along the rods C and E, to adjust it to the length of the surface to be held for gilding, and is secured in place, when adjusted by the set-screw F, as shown in figs. 1 and 3.

G are catches attached to the lower side of the arms B, to receive and hold the ends of the plate, the surface of which is to be gilded.

H is a lever, pivoted, at or near its middle part, in a groove in the under side of the arms B, and the position of which is adjusted by the set-screw I, so as to hold the plate to be gilded at the desired inclination.

J is a long screw passing through the three arms B, and swivelled to the outer arm, or arms B, so that by turning the said screw J in one or the other direction, the middle arm B may be moved back and forth, to adjust it in the desired position.

K is a block, to which the gold-leaf book is attached, and which is made with a rib, or tongue upon its lower side, which enters and slides along the rack L, so that the block, and, consequently, the book, may be adjusted in the desired position.

Upon the lower part of the forward edge of the block K is cut an inclined groove, as shown in fig. 5, to receive the catches M, which are pivoted in recesses in the rack L, to hold the block K in its exact position.

The catches M are held forward in working-position by the coiled springs N, and may be withdrawn from the block K, to enable it to be moved back and forth, or adjusted by pressing upon the knobs O, connected with said catches, and projecting from the forward edge of the rack L.

When the book-block is properly adjusted, the blank leaves of said book are turned back, and are held by the forward ends, or hands of the arms P, the rear ends of which are hinged to supports attached to the table A, and which are held down with the requisite pressure to hold the said blank leaves, by the springs Q, pressing upon their upper sides, as shown in figs. 1, 2, and 3.

R is a board, pivoted at or near its rear edge to supports attached to the table A, so that its forward end may be raised, to raise the forward ends of all the arms P at the same time.

To the under side of the board R is attached a rod S, which passes down through a slot formed in the table A, and which has a notch, or catch formed in the side of its lower end, to receive the catch-bar T, to hold the said board R down.

The catch-bar T is pivoted at its inner end to the table A, its free end moves back and forth in a keeper attached to said table, and it is held forward against the catch S by a spring U, attached to said table, and the free end of which presses against the said catch-bar T.

The board R is raised, when the catch S is released from the bar T, by coiled springs V, placed in recesses in the table A, and the upper ends of which rest against the under side of the board R.

W are arms, exactly like the arms B, and provided with catches X, levers Y, and set-screws Z, similar to the catches G, levers H, and set-screws I, of the said arms B, for the purpose of holding and adjusting the inclination of the frame A', in which is secured the pattern, according to which the gilding is to be done.

The arms W are connected to each other in pairs by rods B', and they are pivoted to a long rod, C', secured to supports D', attached to the table A.

The arms W slide freely upon the rod C', so that the pattern can be conveniently adjusted in the desired position upon the plate to which the gold-leaf has been applied, in the manner hereinbefore described, or in any other convenient manner.

Having thus described my invention,

I claim as new, and desire to secure by Letters Patent—

1. The three pivoted holder-arms B, two stationary and one adjustable, provided with catches G, pivoted levers H, and set-screws I, the connecting-rod E, and pivoting-rod C, in combination with each other, and with the rack L, substantially as herein shown and described, and for the purpose set forth.

2. The combination of the long adjusting-screw J with the pivoted holder-arms B, substantially as herein shown and described and for the purpose set forth.

3. The book-holder block K and spring-catches M, in combination with the grooved rack L and plate-holder B C E, substantially as herein shown and described, and for the purpose set forth.

4. The combination of the arms P and springs Q with

the grooved rack L, book-block K, and plate-holder B C E, substantially as herein shown and described and for the purpose set forth.

5. The combination of the pivoted board R, springs V, catches S, and spring-catch bar T U, with the spring-arms P Q, substantially as herein shown and described, and for the purpose set forth.

6. The combination of the two pivoted adjustable arms W, provided with catches X, pivoted levers Y, and set-screws Z, the connecting-rod B', and pivoting-rod C', with each other, substantially as herein shown and described and for the purpose set forth.

JAMES LICK.
